UNITED STATES PATENT OFFICE.

WILLIAM A. HOLNAGEL, OF SAGINAW, MICHIGAN.

INTERLOCKING LEVER FOR SILO-DOORS.

941,679.

Specification of Letters Patent. Patented Nov. 30, 1909.

Application filed April 5, 1909. Serial No. 487,992.

To all whom it may concern:

Be it known that I, WILLIAM A. HOLNAGEL, a citizen of the United States, residing at Saginaw, in the county of Saginaw and State of Michigan, have invented certain new and useful Improvements in Interlocking Levers for Silo-Doors; and I do hereby declare the following to be a full, clear, and exact description of the invention, 10 such as will enable others skilled in the art to which it appertains to make and use the same.

My invention relates to silos and more particularly to means for locking silo doors 15 in position.

As is well known, the longitudinally extending opening in a silo is closed by means of a series of doors arranged end to end and held in place by means of locking levers. 20 As the ensilage is used, by being fed to the cattle, the upper doors are removed in succession.

It has been customary, in order to permit the farmer to remove the upper door, to so 25 form the door locking levers that their handles, together with the cross-girts on the ordinary steel frame silo, forms a ladder, permitting the farmer to ascend and remove the uppermost door. These levers are generally secured to the doors with their ends 30 adapted to over-lap the door frame or casing of the silo, and in order to remain in horizontal position when supporting the weight of a person ascending the silo, it is necessary 35 that the ends of the levers engaging the door frame or casing shall be held against movement. Otherwise, in case the levers should yield or give under the weight of the farmer, the latter would be precipitated 40 to the ground, to his probable injury. Such accidents are very apt to occur, because, owing to the shrinkage or warpage of the silo frame, the means depended upon to limit the movement of the levers and retain their 45 handles in horizontal position, is moved out of its proper position and does not serve as an abutment to be engaged by the operative end of the lever. Also, owing to wear, such abutments may not fulfil their purpose.

50 The object of my invention is to provide a locking means for retaining silo doors in position, such locking means, together with the cross-girts, shall serve as a ladder which can not yield beneath the weight of anyone 55 ascending the ladder, even though the operative outer ends of the levers should acci-

dentially become disengaged from the door frame of the silo.

Another object of my invention is the provision of a locking lever which renders 60 unnecessary the provision of any abutments or other means on the door frame for engagement by the operative end of the lever and which will retain the doors in place.

To these and other ends, my invention 65 consists in certain novel features and combinations of parts, such as will be more fully described hereinafter and particularly pointed out in the claims.

In the accompanying drawings, Figure 1 70 is a perspective view of a silo door equipped with my invention, dotted lines showing the positions of the levers in released position. Fig. 2 is a similar view, showing its application to a silo, and Fig. 3 is a detail top plan 75 view.

A indicates a fragmentary portion of a silo, 1 being the door opening, 2, the door frame, and 3, the door. These elements are constructed in any suitable manner and form 80 no portion of my invention.

The door is provided near its opposite longitudinal edges with a pair of levers. Preferably, I form such levers each with a head 4 pivotally secured to the door as at 5, 85 the outer end of such head being adapted to over-lap the door frame 2.

As one means for insuring that the outer end of the lever will firmly engage the door frame to retain the door 3 in position, I 90 may provide the under face of the head 4 with a rounded or cam surface.

The inner end of the head is provided with an arm 6, by means of which the lever is oscillated into and out of position. The 95 levers are located preferably opposite and in alinement with each other, the inner end of one arm being provided with a recess 6', in which is received a tooth 7 carried by the opposite end of the lever when the levers are 100 being brought into horizontal alinement.

The extreme inner ends of the arms are each equipped with abutments 8, 8, having flat faces, adapted to engage each other when the arms are in horizontal position, to 105 prevent further downward movement of the levers. These abutments project upwardly from the arms to effect this result.

In operation, as the ensilage is deposited in the silo, the doors are all in place, closing 110 the door opening 1 from bottom to top, the levers being in the positions shown in full

lines in Fig. 1, with their ends intermeshing and the abutments 8, 8, engaged. This construction not only serves as a ladder, but also as a brace for the door. When the 5 ensilage is to be used, the farmer climbs to the uppermost door which he releases by forcing the inner ends of the levers upwardly, as shown in dotted lines in Fig. 1, thereby disengaging the outer ends of the 10 levers from the door frame.

So far as I am aware, it is new to provide interlocking levers for silo doors. It is also new, so far as I am aware, to connect the inner ends of the levers in any manner. It 15 is also new, so far as I am aware, to provide the inner ends of silo door levers with the particular interlocking means illustrated and described.

It is, of course, obvious that changes might 20 be made in the form and arrangement of the several parts described, without departing from the spirit and scope of my invention.

Having thus fully disclosed my invention, 25 what I claim as new, is:—

1. The combination with a suitable structure and a door therefor, of a pair of levers pivotally secured to the door, and means for preventing the depression of the inner 30 ends of the levers past a predetermined point, irrespective of the engagement of the outer ends of the levers with the structure.

2. The combination with a suitable structure and a door therefor, of a pair of levers 35 pivotally secured to the door, and means carried by the inner ends of the levers for preventing the depression of the levers past a predetermined point.

3. The combination with a suitable structure and a door therefor, of a pair of levers 40 pivotally secured to the door, and coacting intermeshing means carried by the inner ends of the levers for preventing the depression of the levers past a predetermined point.

4. The combination with a suitable structure

having an opening therein and a door for closing the opening, of a pair of oppositely located levers pivoted intermediate their ends to the door, the outer ends of the 50 levers adapted to engage the structure, the inner ends of the levers adapted to abut each other when the levers are in horizontal position.

5. The combination with a suitable structure 55 having an opening therein and a door for closing the opening, of a pair of oppositely located levers pivoted intermediate their ends to the door, the outer ends of the levers adapted to engage the structure, the 60 inner ends of the levers adapted to abut each other when the levers are in horizontal position, the inner end of one lever carrying a projection receivable in a recess in the opposite lever to releasably lock the levers in 65 substantially horizontal position.

6. A silo comprising a structure having a door opening, a door for the opening, and levers movably secured to the door, the inner 70 ends of the levers adapted to interlock.

7. A silo comprising a structure having a door opening, a door for the opening, levers movably secured to the door, and abutments carried by the inner ends of the levers and adapted to contact with each other to afford 75 a positive limit to the movement of the levers in one direction.

8. A silo comprising a structure having a door opening, a door for the opening, levers movably secured on the door, the under 80 faces of the outer ends of the levers being convex and adapted to overlap and frictionally engage the silo structure adjacent to the door, the inner ends of the levers carrying opposed abutments adapted to engage 85 when the levers are in horizontal position.

In testimony whereof, I affix my signature in presence of two witnesses.

WILLIAM A. HOLNAGEL.
